ABSTRACT: Novel assembly means are provided for aligning and unifying a plurality of similar packages, as of rolls of cellophane. Each package has end sections, which extend somewhat beyond the sidewalls and which have a plurality of suitably shaped notches. Spools, having hub portions adapted to engage the mating surface of the notches, and having flanges at each end adapted to engage end section walls around the notches, firmly retain the assembly together by preventing horizontal movement of the packages relative to each other. A curved or tapered surface is provided on one or both of the mating spool and end support notches in order to facilitate the desired alignment of the packages into a unitary assembly, from which the individual packages are easily and rapidly removable when desired.

PACKAGE ASSEMBLY

BACKGROUND OF THE INVENTION

This invention relates to the assembly of similar packages to provide readily stacked or nested multiple units which are firmly locked together for transportation or storage, but from which individual packages are easily and quickly removable when so desired. The novel means and method of assembly are particularly applicable to and illustrated by the ready stacking of rolls of elongated webs of cellophane, paper, cloth, foil or films, for example, cellulose esters or ethers, vinyl polymers, polyamides, polyesters or polyolefines. Individual rolls of such webs which must be stored and transported are frequently of substantial weight, amounting to hundreds of pounds and up to 1,000 pounds or more.

It has been the practice to assemble a number of such rolls on pallets or skids for transportation, with provision being made for strapping and fastening the rolls to each other and to the pallet. It has been a time-consuming and expensive operation to provide strong and stable assemblies of rolls adequate to supply the necessary protection to the individual packages and, likewise, the disassembly at the destination involved similar disadvantages. Various fastening expedients have been utilized heretofore to provide the required strength and rigidity of assembly, but none of these had the desired attributes of ease, speed and economy of application or disassembly.

SUMMARY OF THE INVENTION

In accordance with the present invention, the problems and disadvantages, which were unavoidable with the practices and proposals of the prior art, have been overcome by the provision of novel assembly means. These are essentially comprised of flanged spools adapted to mate with package end supports to prevent any substantial horizontal movement of contiguous packages relative to each other, thereby firmly retaining the packages in the desired rigid assembly, while permitting the easy and rapid removal of individual packages when desired. Each of the spools is provided with a hub portion, which engages the mating surface of notches or recesses in the periphery of adjacent end supports, and having a flange at each end of the hub engaging the end support wall. A further advantageous feature is the provision of a curved or tapered surface on one or both of the mating spool and end support notches in order to facilitate the desired alignment of the packages.

BRIEF DESCRIPTION OF THE DRAWING

The present invention will be clearly understood as illustrated in the accompanying drawing, in which:

FIG. 1 is a perspective view of an embodiment of this invention, showing two packages stacked in alignment and rigidly assembled for storage or shipment;

FIG. 2 is an exploded perspective view of the elements of the package assembly shown in FIG. 1;

FIG. 3 is an enlarged fragmentary sectional view taken along line A-A of FIG. 1;

FIG. 4 is a perspective view of a preferred embodiment of this invention, showing a plurality of packaged rolls of film stacked in alignment and rigidly assembled;

FIG. 5 is an end view of a modification in accordance with the invention wherein the alignment and rigidity of the assembly is increased by the use of additional spools at the base and corners of the end supports.

DESCRIPTION OF PREFERRED EMBODIMENTS

An illustrative example of a multiple package assembly in accordance with the invention is shown in FIGS. 1-3 of the drawing, wherein multiple packages are aligned and held together by means of spools which conform with notches in the package end sections, so as to provide effective resistance against relative horizontal movement.

Packages 1 are provided with end sections 2 which are larger in cross section than the body of the packages so that the end peripheries extend somewhat beyond the sidewalls as shown. The end sections are provided with suitably shaped and spaced notches 3 adapted to receive spools 4. The spools comprise a hub portion 5 and flanged heads 6, which are preferably of circular cross section with the hub surface conforming with the surface of the notches 3. As shown, the inner edge of flanged heads 6 may be rounded or tapered inwardly for the purpose of facilitating the proper alignment in stacking the assembly. With a spool in position within each exposed notch of a lower package, the upper package can be placed over it at approximately its desired location, and because of its weight, it will be guided by the mating contoured surfaces and drop into the desired aligned location.

With the assembly completed as shown in FIG. 1, resistance against longitudinal horizontal movement of each package relative to its neighboring packages is provided by the flanged heads of the spools and against lateral movement by the spool hubs. While FIG. 1 shows an assembly of two packages, it will be understood that a greater number may be similarly assembled.

The ease of alignment can likewise be increased by the additional provision of inwardly contoured surfaces at the edges of notches 3, or can be accomplished satisfactorily by such provision, without the need for any inward rounding or tapering of the flanged heads. In the latter case, a larger area of the flanged heads is contiguous to end sections 2 and would tend to increase the rigidity of the assembly.

If desired, the rigidity of assembly may be increased by applying either or both longitudinal or lateral binding tapes or straps around the united packages. Removal of the individual packages from the assembly, when desired, is readily accomplished by lifting away the uppermost package or packages, and removing the exposed spools, whereupon the remaining packages are easily removable.

Satisfactory spools and package end sections may be made of wood, metal, plastics, ceramics, vulcanized fiber or other suitably treated compressed paper, composite board, mineral board, or other material of suitable strength and resistance to withstand long use and rough handling. Spools of any tough hard wood such as hard maple are generally preferred, although in some applications spools of molded plastic are also highly advantageous, preferably of plastics having high impact strength, for example, of polypropylene, polystyrene, polyacetals, polycarbonates, nylon, or fiber-filled polymeric compounds. Molded spools may be provided having an axial opening through the hub or other internal hollows to facilitate the molding process as well as weight reduction while furnishing the requisite strength and desired endurance properties.

While the spool has been shown as having a circular cross section, which is preferred, the invention is not limited thereto as advantageous results are readily attained with others. For example, either or both the hub and the mating notch may have an elliptical or polygonal cross section so as to increase the resistance against the relative movement of the adjacent packages. Likewise, the self-alignment feature may be enhanced by the provision of spools provided with a hub surface which tapers inwardly from both ends and conforming notch surfaces.

A preferred embodiment of the invention is illustrated in FIG. 4 representing an assembly of large packaged rolls of cellophane stacked for shipment or storage. Four packaged rolls are shown, it being clear that additional rolls may be similarly stacked therewith horizontally or vertically. Each package 11 contains a cylindrical roll of cellophane convolutely wound on a hollow cylindrical core, not shown in the drawing. For example, the core of heavy cardboard may have a diameter of about 6 inches and the roll of film may weigh about a 1,000 pounds. The roll may be provided with a suitable outer wrapping of kraft paper or of plastic film. Each package is completed by attaching an end section 12 at both ends, for example, by aligning the end of the core with the central opening of the section

and forcing a closely-fitting flanged plug 17 into fastening position

Each packaged roll 11, complete with end two parallel sections 12 fastened thereto, is stacked in turn with other similar rolls after inserting spools 14, as described in connection with the previous embodiment, in conforming notches 13, thus to form a rigid aligned assembly. The bottom row of packages is first assembled on the floor of the skid or pallet as described above, followed by the succeeding row or rows, each package being lowered into approximate position after the spools have been inserted in the corresponding notches. The desired alignment is obtained through the interaction of the conforming contoured surfaces of the spools and notches, and a stable assembly results because of the resistance to relative horizontal movement of the packages effected by the spool hubs and flanged heads, particularly as enhanced by the considerable weight of each package.

The ease and rapidity of such assembly likewise characterize the operation of removing individual packages when desired. This merely requires, after removal of any binding tapes which may have been used, the lifting of each package in turn from the assembly, followed by the removal of the exposed spools.

The rigidity and alignment of the packages in this embodiment is enhanced by the provision of lateral notches and mating spools, between the end sections of horizontally adjacent packages. For convenience, such lateral notches are downwardly recessed, as shown in FIG. 4, so that the spools may readily be inserted and will stay in place prior to the stacking operation. Although the spool is then not centrally placed between the adjacent vertical edges of the adjacent end sections, the flanged head sufficiently overlaps both to maintain the desired alignment. The lateral notches may be provided in both adjacent vertical edges, for example, having any suitable form, such as triangular or semicircular, and the spool may be inserted with suitable retaining means, as by areas of pressure-sensitive adhesive, prior to the assembly of the packages.

Referring to FIG. 5, an embodiment of the invention is represented which includes a number of modifications. It will be noted that the end sections 22 are provided with notches 23 at the center and corners of each peripheral edge of the end section. These notches are contoured to mate with the spools 24, which have the structure as described above in connection with the previous embodiments.

An additional feature is that the floor upon which the as-

sembly rests, which may be a storeroom floor or a skid or pallet surface, is provided at the predetermined areas either with half spools fastened thereto or contoured depressions into which spools are inserted. Thereby, the bottom row of packages is aligned properly and maintained in said alignment.

Furthermore, the provision of properly recessed corners, for the reception of spools between three or four adjacent packages, tends to provide maximum rigidity of assembly for the least number of spools. The packages in successive higher rows may be superposed directly on a package below or may straddle two such packages, as indicated in dotted lines, to provide an assembly of maximum stability.

Accordingly, it will be understood that the package assembly means and method in accordance with the present invention are widely applicable to provide readily self-alignment and locking together of stacked packages and, at the same time, the easy removal of individual packages when desired. Modifications may therefore be made in the specific illustrative details within the spirit and scope of the appended claims.

20 What I claim is:

1. An interlocked and aligned assembly of like packages each having a projecting wall fastened thereto at both ends and each said wall having a plurality of spaced peripheral notches thereon, wherein each said package consists of a convolutedly wound elongated web, said assembly comprising removable spools positioned in opposed notches of adjacent packages, said spools having a hub portion coextensive with said notches and terminated at each end by a flanged head, and said spools and notches being shaped to effect the self-alignment and interlocking of said assembly.
2. An assembly as set forth in claim 1, wherein said spool hubs and said notches have conforming surfaces.
3. An assembly as set forth in claim 1, wherein said spools have a curvilinear cross section.
4. An assembly as set forth in claim 1, wherein said flanged heads overlie the end walls of a plurality of said packages.
5. An assembly as set forth in claim 1, wherein said notches are located substantially symmetrically on each package end wall.
6. An assembly as set forth in claim 1, wherein said notches include one at each package end wall corner.
7. An assembly as set forth in claim 1, wherein the bottom packages include said notches and spools at the base thereof, whereby to effect alignment and interlocking with a supporting surface.
